UNITED STATES PATENT OFFICE

CLAUDE M. DIBBLE, OF JOLIET, ILLINOIS, ASSIGNOR TO MOORE BROTHERS COMPANY,
OF JOLIET, ILLINOIS, A CORPORATION OF ILLINOIS

STOVE CONSTRUCTION

Application filed August 4, 1928. Serial No. 297,462.

This invention relates to stove constructions, and has for its general object to provide an improved construction facilitating the assembly of the parts and the application of insulating packing material to the surrounding walls of the heating chamber.

Numerous other objects and advantages of the invention will be apparent as it is better understood from the following description, which, taken in connection with the accompanying drawings, discloses a preferred embodiment thereof.

In the drawings:

Figure 1 is a front elevation of one type of stove constructed in accordance with the invention;

Fig. 2 is a vertical section of the same taken longitudinally through the heating chamber;

Fig. 3 is a horizontal section through the heating chamber taken on line 3—3 of Fig. 2;

Fig. 4 is a perspective view on a reduced scale showing the assembly of the inner and outer casing walls, or shells, of the heating chamber;

Fig. 5 is an enlarged detailed fragmentary vertical section showing the mode of attachment of the heating chamber walls to the front framework of the stove, and

Fig. 6 is an enlarged detailed fragmentary horizontal section showing the same construction as Fig. 5.

The illustrative stove is of the electric heater type. The invention has one important application, for example, to electric stoves, because such stoves ordinarily require the application of an insulating packing material to the walls of the heating chamber, and, as will hereinafter appear, a stove constructed pursuant to the invention greatly facilitates the application of such packing material to the heating chamber walls. This electric stove includes a surrounding outer casing 11 comprising the two side vertical walls 12, the top 13, the back wall 14 and the front door frame 15, all assembled into a substantially rectangular cabinet supported upon the four corner legs 16.

A stove of this type may have its side, back and top walls constructed of sheet metal plates assembled in any suitable manner, and

its front door frame 15 made of hollow castings including the top casting 17, the bottom casting 18 and the two vertical side castings 19. These door frame castings are formed each with the front faces or connecting portions 20 bent at their outside edges 21 into the rearwardly extending outer flanges 22 and also bent at their inner edges 23 into the inwardly extending door-receiving flanges 24. At their inner edges 25, these door-receiving flanges are bent into door-stop flanges 26 located along the four edges of the opening against which the door is mounted and lying in a plane substantially parallel with the main plane of the door to limit the inward closing movement of the door.

The door 27 comprises an outer plate 28 made of a suitable casting and an inner plate 29 having forwardly projecting flanging 30 extending along its top, bottom and sides. 70 This flanging 30 is secured to the inner face of the front door plate 28, and the space provided between the rear surface of the front door plate 28 and the rear plate 29 is filled with a suitable insulating packing material, such as mineral wool, as shown at 31. The door 27 is mounted to swing on a horizontal axis at its bottom in any suitable manner and is provided near its top with a suitable handle.

The door is a part of the casing or cabinet 11 and the flanging 30 engages the presented casing or cabinet surfaces when the door is closed. The heating chamber or unit is separate from this casing and is separately constructed.

As shown in Figs. 2 and 3, the front ends of the side plates 12 and the top plate 13 of the outer casing are provided with recessed flanged portions 32 which underlap 90 and are secured in any suitable manner to the rearwardly projecting outside flanges 22 of the vertical and horizontal door frame castings.

The above described construction provides 95 a rigid yet readily assembled outer cabinet in which the heating chamber casing 33 is mounted. This heating chamber casing is substantially rectangular in shape, as shown, and when mounted within the cabinet 11 may 100

be supported at its bottom upon pedestals 34 upstanding from the bottom of the cabinet. This casing 33 is closed at its vertical side, top, bottom and rear walls, but open in the front at 35 adjacent the door 27 and provides a substantially rectangular heating chamber for the stove.

The illustrative heating chamber 33 is constructed of an inner shell 36 and an outer shell 37 spaced from the inner shell at each 10 of the vertical side, top, bottom and rear walls thereof to provide a surrounding space 38 for the insulating packing material.

The inner shell 36 is made preferably of the side, top and bottom sheet metal wall plates 39, each of which is bent at its forward edge 40 into a flange 41 projecting parallel with the door stop flanges 26. The back of the inner shell 36 is closed by a sheet metal back plate 42 provided along the vertical side, top 20 and bottom edges with rearwardly projecting flanges 43 extending in planes parallel with the corresponding walls of the inner shell. This construction permits the back plate 43 to be applied readily in place and secured to the vertical side, top and bottom walls 39 of the inner shell, to close the back of said shell.

The outer shell of the heating chamber casing is made of vertical side, top and bottom plates 44 assembled to form a substantially rectangular casing adapted to surround the inner shell 33, with all of the walls and the back of the outer shell 37 spaced from the corresponding walls of the inner shell. At 30 their front edges, the top, bottom and vertical side walls 44 of the outer shell are bent into flanges 45 which underlap and are fastened suitably to the flanges 41 of the walls of the inner shell 36. The back of the outer shell 37 is closed by a back plate 46 provided with peripheral flanging 47 formed similarly to the flanging 43 of the back plate 42, and engaging in like manner the four walls 40 of the outer shell 37.

At its front, the heating chamber casing 33 may be secured to the door framework by screws 48 (see Figs. 5 and 6) passed through the door stop flanges 26 and the lapping flanges 41 and 45 of the four walls of the inner and outer shells 36 and 37 of the heating chamber casing.

In the illustrative stove a suitable electric heater 49 is supported on pedestals 50 upstanding from the bottom of the inner shell 36 of the heating chamber. The terminal 55 of this heater passes to the outside of the stove through registering holes in the walls 42, 46 and 14 and may be connected outside 60 the back wall 14 of the stove with any suitable source of supply of electricity.

The above described construction of the heating chamber casing 33 provides not only a structure which is simple and easy to manufacture and assemble, but also one in which

the packing may be readily applied so as, with the exception of the open front, to entirely surround the heating chamber. The packing ordinarily provided in structures of this character is mineral wool, a material somewhat difficult and disagreeable to handle. The improved structure of the heating chamber permits ready application of the packing since the inner and outer shells may be first entirely assembled, before any packing is applied, with the single exception of the back plate 46 of the outer shell 37. After having assembled the inner shell 36 and applied its back plate 42, the outer shell is placed over and around the inner shell so that the front flanges 45 of said outer shell engage the companion flanges 41 of the inner shell. The insulating material, indicated at 52, may then be readily packed into the space provided between the top, bottom and side walls 39 and 44 of the inner and outer shells and also spread over the back plate 42 of the inner shell. As soon as the required amount of insulating material has been applied, the back plate 46 of the outer shell may be set into place readily without disturbing any of the packing. Moreover, the construction permits easy access to the packing by the mere removal of the back plate 46 of the outer shell, whenever it is desired to remove and replenish the packing.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. Moreover, it is not indispensable that all features of the invention be used conjointly, as they may be advantageously employed in various sub-combinations and other combinations.

I claim:

1. A stove construction comprising, in combination, an outside cabinet provided with a front door frame having door stop flanging inset from the main plane of the front surface of said cabinet, and a heating chamber casing within said cabinet, including, an inner shell closed at the back and the front-to-rear walls of which are provided with flanging projecting substantially parallel with and adapted to engage said door stop flanging, and an outer shell of which the front-to-rear walls are provided at their front ends with inwardly projecting flanging to lap the outwardly projecting flanging of said inner shell, means for securing said heating chamber casing within said cabinet, and a removable back for said outer shell adapted to engage said front-to-rear walls of said shell, said outer shell being spaced from said

- inner shell to receive an insulating packing applicable between the front-to-rear and back walls of said inner and outer shells.
2. A stove construction comprising, in combination, an outside cabinet provided with a door frame having door stop flanging inset from the outer plane of said frame, and a heating chamber casing within said cabinet, including, an inner shell closed at the back, an outer shell spaced from and surrounding the front-to-rear walls of said inner shell, said shells being provided with companion flanging at their front ends secured to the door stop flanging of said door frame, packing interposed between the front-to-rear walls of said inner and outer shells and against the back wall of said inner shell, and a separate back for said outer shell applicable thereto in spaced relation in respect of the back wall of said inner shell.
- 15 3. A heating chamber unit comprising, in combination, an inner shell, including, front-to-rear walls and a back wall, said front-to-rear walls having outwardly projecting flanging, and an outer shell adapted to surround said inner shell and having front-to-rear walls spaced from the corresponding walls of the inner shell and provided at their front ends with inwardly projecting flanging companion to and arranged to lap the flanging of said inner shell walls, and a separate back wall for said outer shell having rearwardly projecting flanging adapted to engage said front-to-rear walls of said outer shell.
- 20 4. A heating chamber unit comprising, in combination, an inner shell, including, front-to-rear walls and a back wall, said front-to-rear walls having outwardly projecting flanging, and an outer shell adapted to surround said inner shell and having front-to-rear walls spaced from the corresponding walls of the inner shell and provided at their front ends with inwardly projecting flanging companion to and arranged to lap the flanging of said inner shell walls, and a separate back wall for said outer shell.
- 25 5. A stove construction comprising, in combination, a surrounding outside cabinet, a heating chamber unit mounted within said cabinet, including, an inner shell, an outer shell surrounding and spaced from said inner shell, packing interposed in the surrounding space between said shells, and a separate back wall for said outer shell whereby the packing may be applied to or removed from said packing space subsequent to assembly of said inner and outer shells.
- 30 6. A heating chamber unit comprising, in combination, an inner shell constituting the top, bottom and side walls of the heating chamber and an outer shell surrounding said inner shell and spaced from the walls thereof and having a removable back wall whereby packing may be inserted in the space provided between said shells subsequent to their

assembly, said inner and outer walls having companion flanging in lapping relation at the front of said heating chamber unit.

7. A stove construction, comprising a casing having an aperture in its front, a door, and a heating chamber unit mounted within said casing and comprising an inner shell, an outer shell surrounding said inner shell and spaced therefrom, and packing interposed between the said shells, said heating chamber casing being open at its front and said casing aperture and said heating unit being closed by said door.

8. In a stove construction, the combination of a cabinet providing an oven space defined by top, side and back walls and an apertured front wall, a separately constructed heating chamber unit comprised of top, side and back walls, each formed of an outer and inner metal sheet with intermediate insulated packing, said heating chamber unit being insertable within the oven space of said cabinet, and a door for closing the aperture in the front wall of the cabinet and for forming the front wall of said oven when in closed position.
